UNITED STATES PATENT OFFICE.

HARRY M. PFLAGER, OF ST. LOUIS, MISSOURI, ASSIGNOR TO THE LOCOMOTIVE TENDER FRAME COMPANY, OF ST. LOUIS, MISSOURI, A CORPORATION OF DELAWARE.

LOCOMOTIVE-TENDER UNDERFRAME.

1,047,442.

Specification of Letters Patent. Patented Dec. 17, 1912.

Application filed October 28, 1911. Serial No. 657,266.

To all whom it may concern:

Be it known that I, HARRY M. PFLAGER, a citizen of the United States, residing at St. Louis, Missouri, have invented a certain new and useful Improvement in Locomotive-Tender Underframes, of which the following is a full, clear, and exact description, such as will enable others skilled in the art to which it appertains to make and use the same, reference being had to the accompanying drawings, forming part of this specification, in which—

Figure 1 is a plan view of a locomotive tender underframe of my improved construction. Fig. 2 is a vertical section taken lengthwise through the center of the underframe. Fig. 3 is a front elevation of the underframe. Fig. 4 is a transverse section taken on the line 4—4 of Fig. 1. Fig. 5 is a transverse section taken on line 5—5 of Fig. 1. Fig. 6 is a rear elevation of the underframe.

This invention relates to new and useful improvements in locomotive tender underframes, the object being to lower the center of gravity of the tank carried by the frame. In locomotive tenders now commonly in service, the tank rests upon a floor which is in turn supported by an underframe which varies from 10 to 15 inches in depth. As the floor level of various types of locomotives now in use is relatively high, and as it is necessary to locate the floor of the tender on the same plane, this leads to raising the center of gravity of the tank to a comparatively great distance from the rail which produces a strong tendency of the tank to overturn when rounding curves.

By my improvement the center of gravity of the tank is lowered and the above mentioned tendency to overturn is thus overcome. The tank is bifurcated at its front portion to provide the usual receptacle for coal, and if desired, the side and rear walls may be raised above the tank proper to increase the coal carrying capacity of the tank. The tank is further provided with a recess in the under side of its rear portion which enables the tank to straddle the underframe

and extend down on each side thereof, and between the front and rear end sills whereby I am able to utilize for tank purposes a large portion of the space ordinarily occupied by the tender underframe. The sides of the central portion of the tank are supported by suitable cross bearers which extend laterally from the central portion of the center sill of the tender frame. The top surfaces of these cross bearers occupy a plane a substantial distance below a plane occupied by the top of the center sill and the usual side bearings (not shown) are applied to the sides of the end portions of these cross bearers. By extending the side members of the tank down between the end sills of the underframe, the tank is held firmly in position and is prevented from sliding off of the underframe in the event of collision, and as the tank straddles the center member of the underframe, sidewise displacement is also prevented.

In the drawings 1 designates the front end sill of the tender frame and 2 the rear end sill. The front end sill is preferably provided with the usual opening 1^a for a pocket coupler by means of which the tender is coupled to the locomotive. The rear end sill 2 is preferably of the usual box type and provided at its center with a opening 2^a which accommodates the draw bar by means of which the tender is coupled to an adjacent car. Extending transversely beneath this opening 2^a is a detachable draw bar carry iron 3.

4 designates the center sill of the frame which is of the usual box type and having its top and bottom plates preferably perforated for the purpose of lightening the weight of the entire underframe. The ends of the center sill are formed integral with the end sills 1 and 2, and formed integral with the end sills and under portions of the center sill are diagonally disposed braces 5 which materially strengthen the ends of the structure and provide supports for the end portions of the tank located on the frame. Formed integral with the center sill 4 and projecting laterally from the lower portions

of the sides thereof are cross bearers 6 which are preferably hollow, and which serve as supports for the central portion of the tank located upon the frame.

5 The tank, which is supported by my improved frame, is preferably constructed of heavy sheet metal and comprises a rear portion 7, which occupies a position on the rear portion of the underframe immediately adjacent the end sill 2, and formed in the under side of this portion of the tank is a longitudinally extending space 8 which receives the rear portion of the center sill 4. The under side of the portion 7 of the tank 10 rests directly upon a pair of cross bearers 6. The forward portion of the tank is bifurcated and the parts 8 formed by such construction rest upon the forward pair of cross bearers 6 and the extreme forward 15 ends of said parts bear against the rear side of the end sill 1. A floor 9 connects the parts 8 of the tank and said floor lies directly upon the forward portions of the center sill 4. The space above this floor between the parts 8 forms a receptacle for coal, 20 and if desired, a rear wall may be extended upward from the portion 7, and side walls may be extended upward from the sides of the tank to form additional coal space there- 25 by materially increasing the coal carrying capacity of the tender. The extreme under portions of the tank are supported by the braces 5.

My improved tender frame is preferably 30 cast in a single piece, as shown and described, although it is obvious that the frame may be built up from special castings or from ordinary commercial shapes.

A tender under frame of my improved 35 construction is comparatively light in weight, is very strong and rigid, has great carrying capacity and the center of the tank mounted on the underframe is located at a comparatively low point so as to overcome the tendency of the tender to overturn when 40 rounding curves. The tank when properly positioned on the underframe straddles the center sill 1 and rests upon the cross bearers 6 and the diagonally disposed braces 5, with 45 its ends bearing directly against the inner faces of the end sills 1 and 2 and thus said tank is effectually prevented from sliding movement both lengthwise and laterally during service or in case of wrecks.

5 It will be readily understood that minor changes in the size, form and construction of the various parts of my improved tender underframe may be made and substituted for those herein shown and described without departing from the spirit of my invention, the scope of which is set forth in the appended claims.

I claim:

1. A locomotive tender comprising an

underframe consisting of end sills and a center sill, and a tank straddling said center sill with its ends bearing against the end sills whereby said tank is held against longitudinal and transverse movement with respect to the underframe. 65

2. In a locomotive tender, the combination of, an underframe comprising end sills and a center sill, and a tank straddling the center sill, the ends of which tank bear against the inner faces of the end sills. 70

3. In a locomotive tender, the combination of, an underframe comprising a center sill and end sills, a tank arranged between said end sills and supports for said tank, which supports are carried by said center sill. 75

4. A locomotive tender, comprising an underframe, consisting of end sills, a center sill, laterally projecting tank supports on said center sills intermediate of the end sills, and a tank straddling the center sill and bearing upon the lateral supports and against the end sills. 80

5. In a locomotive tender underframe a hollow box shaped center sill, end sills integrally connected to said center sill and diagonally disposed tank supporting members arranged between the lower portions of the center sill and end sills. 90

6. In a locomotive tender underframe, a hollow box shaped center sill, end sills integrally connected to said center sill and diagonally disposed tank supporting members arranged between the lower portions of the center sill and end sills and the top surfaces of which supporting members occupy a plane substantially below the plane occupied by the top surfaces of the center and end sills. 95

7. The combination with a locomotive tender underframe having a center sill and end sills, of a tank straddling said center sill with the side portions of said tank extended downward on the sides of said center sill and the ends of which tank bear against the inner faces of the end sills. 105

8. The herein described locomotive tender underframe formed in a single piece and comprising a box shaped center sill, end sills, diagonally disposed tank supporting members arranged between the end portions of the center sill and the end sills, and tank supporting members projecting laterally from the sides of the center sill, all of which tank supporting members are arranged below the plane occupied by the top surfaces of the center and end sills. 115

9. The combination with a locomotive tender underframe, having a center sill and end sills, of a tank straddling said center sill with the side portions of said tank extending downward to the sides of the center sills, and supports on the center sill for the central portion of the tank. 125

10. The combination with a locomotive tender underframe having a center sill and end sills, of a tank straddling said center sill with the side portions of said tank extending downward to the sides of the center sills, and supports on the center sill for the central and end portions of the tank.

In testimony whereof I hereunto affix my signature in the presence of two witnesses, this 20th day of October, 1911.

H. M. PFLAGER.
